UNITED STATES PATENT OFFICE.

WILLIAM H. PERRY, OF CONCORD, NEW HAMPSHIRE.

DESIGN FOR A MONUMENT.

SPECIFICATION forming part of Design No. 21,410, dated March 15, 1892.

Application filed February 11, 1892. Serial No. 421,193. Term of patent 3½ years.

To all whom it may concern:

Be it known that I, WILLIAM H. PERRY, a citizen of the United States, residing at Concord, in the county of Merrimac and State of New Hampshire, have invented and produced a certain new and original Design for Monuments, of which the following is a specification.

In the following description of my design reference will be made to letters and figures of reference marked upon the accompanying drawing.

The leading features of my design consist in the particular configuration of the base, the pedestal, and the shaft. The base is marked 1 and has four vertical sides terminating at its top in an obtuse frustum 2 of a pyramid. The pedestal 3 has four vertical sides terminating at its top in an acute frustum of a pyramid, (shown at 4.) One or more of the sides of the frustum 4 is ornamented by a raised tablet 5. The shaft 6 has for the main portion of its length four tapering sides meeting at its lower end by means of the caved curves 7 the four short vertical portions 8, which join the frustum 4. The sides 8 have straight upward extensions 9, narrower than the main portions and leaving at each side spaces 10, and the top of said extensions 30 curve upward and toward the shaft, as seen at 11. The shaft 6 terminates at its upper end in a four-sided dome 12, the sides of which meet at an apex 13.

My design further consists in the ornamentation of the sides of the shaft 6, comprising 35 the tablets 14, which join the said shaft at their bottom with the convexed curves 15. The upper edge of said tablets 14 are castellated, as at 16, the flat tops 17 of said castellations or battlements extending inward where 40 they meet the acute frustum of a pyramid, (shown at 18,) said frustum 18 commencing at its bottom at the bottom outside edge of the openings forming the battlements 16 and terminating at its top in the convexed curves 19, 45 which meet the short vertical base portion of the four-sided dome 12, as seen at 20. The ornamentation of the shaft also comprises the tablets 21 22, the adjacent edges of which describe the pointed arches 23 24, respectively. 50

Another feature of my design consists in the ornamentation of the various parts by surfaces of a different character, those surfaces indicated at A being termed "rock-work," those at B "hammered work," and those at C 55 are "polished work."

What I claim as my invention is—

The design for a monument, substantially as herein described and shown.

In testimony whereof I affix my signature in 60 presence of two witnesses.

WILLIAM H. PERRY.
